METHOD OF INCORPORATING LUBRICANT

Walter D. Hodson, Beverly Hills, Ill.

Application March 27, 1936, Serial No. 71,305

4 Claims. (Cl. 117—34.5)

This invention relates to a method of incorporating fluids in cordage.

As set forth in my Patent No. 2,000,951, issued May 14, 1935, the incorporation of a viscous lubricant containing an absorbent fibrous material in cordage adds greatly to the life and usefulness thereof. The incorporation of such lubricants in the cordage presents some difficulties. Various methods of carrying out this incorporation are set forth in my Patent No. 2,028,158, issued January 21, 1936. In carrying out such a method, there is still some difficulty in preventing the throwing off of lubricant in the spool box which rotates 1500 to 1600 times per minute. In my co-pending application Serial No. 53,248, filed December 6, 1935, is suggested one method for eliminating this throwing off, in which the lubricant is fed into the yarn or thread in a tube of fibrous material.

It has now been discovered that lubricant may be incorporated within the yarn and passed through the die, after which a ribbon may be wrapped about the yarn before it enters the spool box.

This invention is also applicable to the incorporation of light oils and fluids in cordage for other than lubricating purposes. For example, it is frequently desirable to apply lubricants for preserving purposes either against insect or bacterial action. This is frequently done in connection with such cordage, as binder twine, and marine cordage. The invention is applicable not only to vegetable cordage but may be applied to wire material. The term "fibrous" has been used herein to cover not only vegetable fibers, but to cover the individual wires in a wire rope strand. Likewise the term "cordage" has been used in the claims herein to include wire ropes.

The invention is illustrated in drawings, in which—

Fig. 1 is an elevation partly in section and partly broken away illustrating a spinning assembly; Fig. 2 is a plan view broken away showing the ribbon feeding mechanism; Fig. 3 is an elevation as viewed along the line 3 in Fig. 2; and Figs. 4 and 5 are detailed views illustrating various methods of winding the ribbon. Fig. 6 illustrates the spool box of which an end is shown broken away in Figs. 1 and 2.

As illustrated in Fig. 1, 1 illustrates a group of fibers which are drawn together within the die 2 and formed into a thread or yarn 3 which is drawn into the spool box 4. Just before the thread enters the spool box it contacts a ribbon 5 of fabric material, for instance, paper or cloth 5,

which is wrapped about the thread by its rotational movement. A paper feeding device 6 is illustrated which may be of any conventional form.

The spool box, which is of the conventional form, comprises a drive shaft 10 which drives the frame 11 through a plurality of gears 12. Normally, the frame 11 will rotate at a speed of as much as 1600 revolutions per minute. Within the frame is mounted a spool 13 upon the spindle 14. The thread enters the apparatus through the opening 15 and is passed out upon the tensioning mechanism 16 and up to the pulley 17 carried by the bar 18 of the frame. The channel member 19 encloses the pulley and slides it back and forth along the bar in order to distribute the yarn equally upon the spool. A friction drive mechanism 20 is provided for the spool in order to accommodate for the increase in diameter thereof during winding.

As is obvious, the yarn upon the frame is subjected to tremendous centrifugal force, by which there is an enormous tendency to throw off any fluid or plastic material upon it.

The ribbon feeding mechanism is mounted on a bracket 7 pivotally mounted on the bolt 8 so that the angle of the ribbon may be changed. The bolt 8 is movable in the slot 9 in the support 10. As a result of this two-fold movement, the ribbon feeding device 6 may be positioned to feed the ribbon at a large variation of angles and thereby at any given rotational and forward speed of the yarn 3 may be made to wrap ribbon about it in various degrees of tightness and with various amounts of overlapping. Figs. 4 and 5 illustrate two different angles and illustrate the effect of such angles on the overlap. An adjustable tensioning device 12 is preferably mounted on the feeding mechanism 6.

A lubricant or fluid feeding device 11 is adapted to feed the lubricant into the center of the yarn prior to its entry into the die.

The fabric employed may be absorbent material such as paper, which will be gradually or rapidly disintegrated by the absorption of lubricant, or it may be a fabric which will maintain its integrity indefinitely and will assist in preventing wear of the yarn material.

A preferred grease may be prepared from a viscous mineral oil, an aluminum soap, and an asphaltic or blown oil. For example, a suitable grease may be prepared of 39 parts of a heavy oil of 190-210 viscosity at 200° F., one part of aluminum oleate, and 50 parts of a blown oil having approximately 100° melt point and a pene-

tration in the order of 200 at 77° F. The fibrous base is incorporated in the lubricant in proportions depending upon the absorbing qualities of the base. A well ground, good quality asbestos 5 may be used in the proportions of 10 parts asbestos to 90 parts of grease, but normally, as set forth in my co-pending application, Serial No. 744,061, filed September 12, 1934, it is preferred to use mixtures of finely ground and coarsely 10 ground asbestos in which generally about 25 parts of total asbestos is used for 75 parts of lubricant.

The foregoing detailed description has been given for clearness of understanding only and 15 no unnecessary limitations should be understood therefrom, but the appended claims should be construed as broadly as permissible, in view of the prior art.

I claim:

20 1. In the incorporation of fluids into cordage yarn wherein rope fibers are introduced into a forming die and the fibers are treated with fluid prior to emergence of yarn from the die and the fluid-treated yarn then passes to a rapidly ro-

tating member upon which the yarn is mounted at a point distant from the center and subjected to great centrifugal action, the step of forming a fabric layer about the yarn between the forming die and the rotating member, whereby throwing off of the fluid therein is prevented. 5

2. The method as set forth in claim 1 in which the fabric is paper.

3. In the incorporation of lubricant into cordage yarn wherein rope fibers are introduced into 10 a forming die and the rope fibers are lubricated prior to emergence of yarn from the die and the lubricated yarn then passed to a rapidly rotating member upon which the yarn is mounted at a point distant from the center and subjected to 15 great centrifugal action, the step of forming a fabric layer about the yarn between the forming die and the rotating member whereby throwing-off of the lubricant therein is prevented.

4. The method as set forth in claim 3 in which 20 the lubricant is a viscous tenacious fiber containing lubricant.

WALTER D. HODSON.
